(57) **CLAIM**

The ornamental design for a wrist support with strap, as shown and described.

DESCRIPTION

FIG. 1 is a top view of the inside surface of the wrist support of the present invention.

FIG. 2 is a top view of the outside surface of the wrist support of the present invention.

FIG. 3 is a top view of the inside surface of the wrist support, showing the back of a hand which is partially inserted into the sleeve thereof.

FIG. 4 is a view of the wrist support as shown in FIG. 3, but with the hand fully inserted in the sleeve and the free end of the wrist support being moved towards closure.

FIG. 5 is a view of the wrist support as shown in FIG. 4, in the fully closed position.

FIG. 6 is a view of the wrist support of FIG. 5 from the palm side; and,

FIG. 7 is a view of the wrist support, having a strap wrapped around the wrist portion.

The strap in FIGS. 1 and 2 have been cut-away for ease of illustration and to show indeterminate length.

The broken line showing of the hand in FIGS. 3-7 is for illustrative purposes only and forms no part of the claimed design.
